(57) **CLAIM**

The ornamental design for a container for laundry detergent, as shown and described.

DESCRIPTION

FIG. 1 is a perspective top view of a first embodiment of the container for laundry detergent in accordance with the new design;

FIG. 2 is a left side view of FIG. 1;

FIG. 3 is a right side view of FIG. 1;

FIG. 4 is a back view of FIG. 1;

FIG. 5 is a front view of FIG. 1;

FIG. 6 is a top view of FIG. 1;

FIG. 7 is a bottom view of FIG. 1;

FIG. 8 is a perspective top view of a second embodiment of the container for laundry detergent in accordance with the new design;

FIG. 9 is a left side view of FIG. 8;

FIG. 10 is a right side view of FIG. 8;

FIG. 11 is a back view of FIG. 8;

FIG. 12 is a front view of FIG. 8;

FIG. 13 is a top view of FIG. 8;

FIG. 14 is a bottom view of FIG. 8; and,

FIG. 15 is a top isometric view of FIG. 8.

The broken lines in the drawings depict portions of the container for laundry detergent device that form no part of the claimed design.
